INVENTOR
J. O. WHEELOCK
by Arthur C. Eckert, Jr.

UNITED STATES PATENT OFFICE.

JAY OTIS WHEELOCK, OF ST. LOUIS, MISSOURI.

PHOTOGRAPHIC DEVICE.

1,180,682.

Specification of Letters Patent. Patented Apr. 25, 1916.

Application filed April 19, 1915. Serial No. 22,511.

To all whom it may concern:

Be it known that I, JAY OTIS WHEELOCK, a citizen of the United States, and resident of St. Louis, State of Missouri, have invented certain new and useful Improvements in Photographic Devices, of which the following is a specification containing a full, clear, and exact description, reference being had to the accompanying drawings, forming a part hereof.

The objects of my invention are to construct a photographic device which may be used in a studio or for home portraiture for producing various effects to be used as a background for pictures, etc. The various effects that may be produced are as follows: a window with any desired view discernible therethrough, the window and view being made as clearly defined or as indefinite as the necessities of the case may require; any scenery screen can be made to appear realistic by means of the device; a dark surface made to appear light and a light surface made to appear dark.

With the above and other objects in view, my invention has relation to certain novel features of construction and operation, examples of which are described in the following specification and illustrated in the accompanying drawings in which—

Figure 1 is a perspective view of a conventional window sash, sill, etc. with my device attached. Fig. 2 is a fragmental sectional elevation taken at 2—2 Fig. 1. Fig. 3 is a sectional elevation of one of the rods used in my device.

In the drawings numeral 4 designates a sill, 5, a head, 6 the inside facing, 7, the upper sash, and 8, the lower sash, and 9 and 10 the lights of glass and 11, the jamb, and 12 the stops of a conventional window easement.

My device consists of an extensible rod composed of two parts 13 and 14 with a screw plug and its point 15 at one extremity and the point 15' at the other together with a set screw 16. By means of this structure, the length of the rod may be changed at will by loosening the set screw 16. The points 15 and 15' enable the rod to be held in a window frame at any point as indicated in Fig. 1. In the form shown in the drawings two such rods are required, although one or more may be used. To the one is at-

tached a translucent screen 17, (made of 55 porous cloth or other similar material) on which is painted, stenciled or otherwise marked, the configuration of a window, etc.; to the other is attached a translucent screen 18 on which is painted, stenciled or otherwise marked the configuration of some desired scenery.

On Fig. 1, a French window 17^a is shown on screen 17, partly broken away, disclosing the scenery 18^a on screen 18 in the rear. 65 By means of the extensible rods, these screens may be used on windows of various dimensions. These screens may be used with any source of light, either natural or artificial, and may be used without a window casing, etc., in which case, the imprint of the entire configuration of a window and easement is made on the screen 17. Screens 17 and 18 may both be mounted on the same rod; 18 always being placed in the rear of 70 17 *i. e.*, to say closest to the source of light; or in a modified form only one screen may be used having the configuration of a window imprinted on one side and of scenery 75 on the other.

The screens may also be positioned adjacent a wall from which reflected light is emitted; thereby darkening or brightening the appearance of the wall depending on the color and consistency of the translucent 80 screens used.

What I claim is—

1. In combination with a source of light, a translucent screen bearing a photographic background mounted in advance of said 90 source of light, a second translucent screen bearing a background for photographic association with the first mentioned background in advance of the first screen and means whereby the screens may be relatively spaced to gradate the visibility of the first mentioned background through the 95 second screen.

2. A photographic background apparatus, comprising a source of light, a pair of 100 translucent screens each bearing a different background, the one visible through the other and means whereby the screens may be differently spaced relative to each other and to the source of light, whereby to gradate 105 the visibility of the rearmost background through the foremost screen and gradate the volume of light through the two screens.

3. In combination with a source of light a translucent screen bearing a photographic background and means for supporting the screen in different spaced relationship with the source of light whereby to tone the background with respect to a photographic instrument.

In testimony whereof, I have signed my name to this specification, in the presence of two subscribing witnesses.

JAY OTIS WHEELOCK.
